UNITED STATES PATENT OFFICE.

JAMES E. WORTMAN, OF KALISPELL, MONTANA.

WRENCH.

1,207,118.

Specification of Letters Patent.

Patented Dec. 5, 1916.

Application filed January 18, 1916. Serial No. 72,772.

To all whom it may concern:

Be it known that I, JAMES E. WORTMAN, a citizen of the United States, residing at Kalispell, in the county of Flathead and 5 State of Montana, have invented certain new and useful Improvements in Wrenches, of which the following is a specification.

My invention relates to wrenches and the primary object thereof resides in the provision of means for pivotally connecting the outer jaw to the shank as well as resilient means for removably holding the movable outer jaw in engagement with a piece of work and thereby permit of the efficient 15 operation of the wrench.

Another object of my invention resides in the provision of a novel guiding and reinforcing means embodying a pair of links for pivotal connection with both the rigid 20 inner jaw and the movable outer jaw thereby guiding the outer jaw during operation, and preventing unnecessary movement of the same.

A further object of my invention resides 25 in the provision of a device of the character described that is simple in construction, efficient in operation and one that can be manufactured and placed upon the market at a minimum cost.

30 Other objects as well as the nature, characteristic features and scope of my invention will be more readily understood from the following description taken in connection with the accompanying drawings and 35 pointed out in the claims forming a part of this specification.

In the drawings, Figure 1 is a side elevational view of my invention; Fig. 2 is a vertical sectional view of my invention taken 40 on line 2-2 of Fig. 3 in the direction in which the arrow points; and Fig. 3 represents a front elevational view of my invention.

Referring more particularly to the drawings in which similar reference numerals 45 designate like and corresponding parts throughout the different views, I provide a shank 1, the inner end of which constitutes a handle, while the opposite end is reduced 50 to provide shoulders 2. An inner jaw 3 having an opening 4 therethrough is associated with the reduced end, and abuts the shoulders 2, being maintained in a substantially rigid position through the medium of 55 a pin 5. The outer surface of the rigid jaw

is provided with teeth 6 for a purpose to be hereinafter described.

For the purpose of pivotally connecting the other jaw of the wrench to the shank, I have provided a connecting link, one end 60 of which is bifurcated to provide arms 7 which are arranged in straddled engagement and pivotally connected to the projecting reduced end of the shank through the medium of a pin 8, the opposite end of the 65 link being reduced as illustrated by the numeral 9. The outer jaw 10 is bifurcated to provide arms 11, said arms being pivotally connected about the reduced end 9 through the medium of a suitable pin 12. The inner 70 surface of the jaw is curved slightly arcuately and is provided with a plurality of teeth 13 which coöperate with the teeth 6 in maintaining a piece of work 14 between the jaws. 75

In order to normally exert a tension on the movable jaw to consequently cause it to coöperate with the rigid jaw and hold an object therebetween, I have provided my improved resilient means in this instance 80 including a leaf spring, one end of which is angularly bent and secured to the shank through the medium of suitable fastening devices 15, the intermediate portion of the spring being bent from the rear face of the 85 wrench and thence extended toward the rear face, the free end thereof being bent outwardly and bearing against the rear end of the outer jaw as designated by the numeral 16. When the jaws are arranged about a 90 piece of work, the tension of this spring serves to hold them in a substantially rigid position with respect to the work and thereby permit of the turning of the wrench.

For the purpose of guiding the movement 95 of the movable jaw during movement, I have provided my arcuate links 17, said links being arranged upon opposite sides adjacent the rear ends of the jaws and pivotally connected at their respective extremities through the medium of pins 18, bearings 19 being provided on the inner faces of the links to facilitate the pivotal connection. These links also serve to prevent transverse movement of the wrench during 100 operation and thereby facilitate the connection of the movable jaw.

The operation of my invention is as follows: When it is desired to use this wrench, the jaws 3 and 10 are pulled away from each 110

other against the tension of the spring and arranged about a piece of work 14, the spring serving to hold them in engagement therewith. The handle end of the shank 5 is now engaged so the piece of work may be turned. The links 17 serve to prevent transverse movement of the outer jaw during the operation of the wrench.

Although I have shown and described the 10 preferred embodiment of my invention, I desire it to be understood that I am not to be limited to the exact details shown, however I desire that great stress be laid upon the arrangement of the means for 15 pivotally mounting the movable jaw as well as the links for preventing unnecessary movement of the movable jaw during operation. Attention is also directed to the connecting link between the shank and the 20 movable jaw, said link being so pivoted as to permit of the jaws contacting with each other and also allowing the movable jaw to be folded into an extended position.

From the above description taken in connection with the accompanying drawings, it 25 can be easily seen that I have provided a device that is simple in construction, containing but a few simple parts that can be cheaply manufactured and assembled and when assembled can be placed upon the market and sold at a minimum cost.

It will be understood that the above description and accompanying drawings comprehend only the general embodiment of my 30 invention and that various minor changes in detail of construction, proportion and arrangement of the parts may be made within the scope of the appended claims and with-

out sacrificing any of the advantages of my invention.

Having fully described my invention 40 what I claim as new and desire to secure by Letters Patent, is:—

1. A wrench including a shank, a rigid inner jaw thereon, a connecting link pivotally mounted on the projecting outer end of the shank, an outer jaw pivotally connected to the free end of the link, means for guiding and limiting the movement of the outer jaw, and a curved leaf spring having 50 one end connected to the shank adjacent the rigid jaw and the outer end thereof exerting its tension on the outer movable jaw whereby the movable jaw will coöperate with the rigid jaw and maintain an object 55 therebetween.

2. A wrench including a shank having a reduced end, a rigid inner jaw on the reduced end, a connecting link pivotally associated with the projecting reduced end, an 60 outer jaw pivotally connected to the free end of the link, arcuate links pivotally connected at their respective extremities to said jaws upon opposite sides thereof for guiding and limiting the movement of the movable jaw, and a leaf spring connected to the shank and bearing against the movable jaw whereby the movable jaw will coöperate with the rigid jaw and maintain an object 65 therebetween.

In testimony whereof I affix my signature in presence of two witnesses.

JAMES E. WORTMAN.
